WILLIAM J. WELSH, OF JERSEY CITY, NEW JERSEY, ASSIGNOR TO HEMENDINGER, ALEXANDER & COMPANY, INC., A CORPORATION OF NEW YORK.

COATING-MACHINE.

1,257,564.

Specification of Letters Patent. Patented Feb. 26, 1918.

Application filed February 18, 1916. Serial No. 79,333.

To all whom it may concern:

Be it known that I, WILLIAM J. WELSH, a subject of the King of Great Britain, and a resident of Jersey City, county of Hudson, and State of New Jersey, have invented certain new and useful Improvements in Coating-Machines, of which the following is a full, clear, and exact description.

This invention relates more particularly to a machine for coating chocolates and candies.

One of the principal objects of the invention is to provide a simple and efficient machine in which the articles to be coated are automatically conveyed through a coating apparatus, and during the passage through the apparatus have chocolate distributed uniformly thereon to form a coating therefor, and said articles conveyed from said coating apparatus or part of the machine in such condition and in a way as will permit the convenient removal of the coated articles.

Other objects of the invention are to provide an apparatus or machine in which the articles may be automatically fed, separated, a coating of chocolate applied thereto and evenly distributed, and during the travel of the articles have an additional fancy line 25 or design placed upon the surface thereof.

Other objects of the invention are to provide a machine which is inexpensive to manufacture; to provide simple means whereby the different parts may be automatically actuated; to provide simple means for cooling the article, and to provide simple means whereby the chocolate or coated material may be maintained in proper condition and suitable for use at all times.

Another object of the invention is to provide simple means whereby the mechanism for placing a special design upon the articles may be readily thrown out of action.

A further object of the invention is to provide simple and efficient means whereby the coated article may be placed in a convenient position and upon aprons or sheets of paper to adapt the article to be readily removed from the machine.

With these and other objects in view, the invention will be more particularly described with reference to the accompanying drawings, which form a part of this application, and will then be pointed out in the claims at 50 the end of the description.

In the drawings, Figure 1 is a longitudinal section, partly broken away, of one form of machine embodying the invention.

Fig. 2 is a fragmentary vertical section of a part of the chocolate feed. 60

Fig. 3 is a plan view partly broken away and partly in section.

Fig. 4 is a transverse section taken on the line IV—IV of Fig. 3, showing means whereby the articles to be coated may be 65 separated before entering the coating apparatus or part of the machine.

Fig. 5 is a fragmentary view in elevation of a part of the means for providing a sinuous line as a decoration or fancy design 70 on the articles as they pass through the machine.

Fig. 6 is a plan view of Fig. 5.

Fig. 7 is a side elevation looking at the side of the machine opposite to that shown 75 in Fig. 1.

Fig. 8 is a fragmentary perspective view showing how sheets of paper to receive the articles may be held on a traveling apron or conveyor; and 80

Fig. 9 is a transverse section showing the means whereby the feed hopper may be vibrated.

The candies or articles to be coated are previously prepared and may be substantially rectangular and of a relatively large size, or of any other desired form. These candies or articles are placed *en masse* in a hopper 10 and said hopper is mounted transversely of the machine between the 85 sides 11 of a main frame or support 12. The frame 12 may be of cast iron or other material, and of any desired length and may be of a more or less skeleton nature so as to be light and easy to manufacture. The 90 sides may be suitably held together by beams or otherwise and at the upper portion thereof have lengthwise rails or beams 13. The hopper 10 is pivotally mounted at 14 to lugs on the rails 13 or otherwise pivotally held 95 thereto and has one end, as 15, closed and the inner end open to adapt the articles to pass from the hopper. The hopper 10 may be provided with lugs 16 at opposite sides thereof and these lugs are adapted to be engaged by cams 17. The cams 17 are disk-like in form having irregular or cam peripheries to adapt the hopper to be vibrated or agitated during the rotary movement of said cams. The cams 17 are secured to a 100 110

rotary rod or shaft 18 at the end of the machine and a second rod or shaft 19 is supported between the sides or rails 18 at any suitable distance from the shaft 18. About 5 said shafts or rolls is an endless carrier or conveyer belt 20. The conveyer belt 20 is located under the mouth of the hopper 10 and during the agitation thereof the candies or articles to be coated will pass from 10 the hopper on to said belt or conveyer 20. As the articles pass along with the conveyer they will be separated suitable distances apart by pins or projecting portions 21 carried by a transversely extending bar 22. 15 The pins 21 are spaced apart according to the size of the articles and have their lower ends in close proximity to the upper surface of the belt, and during the travel of the candies or articles said pins will separate the 20 candies a sufficient distance to permit the same to be individually coated without the coating material closing the space between and uniting any two articles.

A coating part of apparatus 23 of the 25 machine is located adjacent to the inner end of the belt or apron 20. This coating apparatus may be variously constructed. As shown it consists of a casing 24 of substantially box-like form. This casing 24 comprises a cover or top portion 25 and a base or section 26. The base 26 to which the top section 24 is held either detachably or otherwise forms a receptacle for chocolate or other coating material and has a double 30 bottom to form a chamber 27 by which the chocolate or other material may be kept in a proper state. The base 26 is suitably supported by legs 28 of such height as will place the receptacle formed by the base 26 35 somewhat below the plane of movement of the traveling belt 20 and in position for the articles to be received by a metal belt, apron or conveyer 29, said apron 29 being arranged to travel within the casing 20. 40 The apron 29 is of woven metal wire or other construction with interstices or openings which will permit the surplus chocolate to pass therethrough, and said apron passes around a roll or shaft 30 adjacent to the 45 roll or shaft 19 of the traveling belt 20 and at the other end of the casing the belt passes around a shaft or roll 31. The shafts 19 and 30 are spaced close together and are of such size that the articles to be coated will 50 readily pass from the apron or conveyer 20 onto the apron 29 so as to move with the apron 29 through the coating apparatus.

The chocolate in the base 26 is constantly 55 agitated while the machine is in use by a stirrer or mixer 32 which comprises a bar 33 from the upper surface of which projects a plurality of pins 34 of relatively different lengths and which mixer is adapted to rotate within the base 26, said mixer 32 being 60 secured to a rotary shaft 35, the lower end

of which is provided with a bevel gear 36 which is in mesh with a bevel gear 36 held to a rotary shaft 37 so that said shafts will rotate in unison. The chocolate is collected by two wheels, drums or collecting 70 elements 38. These wheels 38 are held to a shaft 39 to rotate therewith and said wheels have their lower portions movable in the chocolate so that as the wheels rotate the chocolate will be collected thereon and 75 carried thereby in the direction indicated by the arrow. At the upper portion of the apparatus is a distributing hopper 40 for the chocolate. This hopper extends the entire width of the wire or metal apron 29 80 and has a trough-like portion 41 across the bottom of which is a sieve-like plate 42 of wire mesh or other form which is adapted to permit the chocolate to pass therethrough to be distributed over the candies or articles 85 to be coated as the latter travels along with the belt or apron 29. The body 41 of the distributing hopper 40 has an inclined front wall 43 and at the upper portion thereof at both ends is provided with scrapers 44 90 whereby the chocolate collected by the wheels 38 at opposite sides of the apparatus may be removed from said wheels and caused to pass into the hopper body 40, the ends of the hopper being inclined as at 44 95 to direct the chocolate into the trough-like body 41 over the bottom 42. The rear side of the body 41 extends upwardly and is bent substantially U-form to fit over and be held to a transversely extending bar 45 by which 100 said trough-like body is suitably supported.

The collecting and distributing hopper 40 for the chocolate will cause the chocolate to be deposited more or less evenly over the candies to be coated during their travel 105 through the apparatus, and to assist in the even distribution of the chocolate and to force any surplus chocolate therefrom, the coated candies are subjected to an air blast or air under pressure through an air inlet 110 pipe 46. This pipe 46 has its lower end flared and spread as at 47 to extend over the entire width of the apron 29, somewhat above the articles and at its outer end and is connected to a source of air supply as a combined blower and exhaust fan. 115 The blower is of such a nature as will force air through the pipe 46 and withdraw the air from the apparatus through a pipe or connection 48. The exhaust connection 48 120 has its lower end near the upper portion of the casing and withdraws the air from the casing as it is forced therein, the U part of the distributing hopper being extended downward to form a wall, as 49, to assist 125 in the separation of the space between the inlet and the exhaust means.

As the articles to be coated travel through the apparatus they pass from the apron or belt 29 to the conveyer belt 50. The belt or 130

conveyer 50 at one end passes around a roll or shaft 51 located adjacent to the roll 31 and close enough to permit the articles to pass readily from one apron to the other, and at the other end of the machine the said apron 50 passes about a rod or shaft 52. On the apron 50 are clips or plates 53 which are secured at one edge to the apron and are offset for the reception of sheets of paper or other material 54 on to which the coated articles pass from the apron 29 and by which they may be placed in a cooling apparatus or otherwise handled as desired. These sheets of paper are easily detached from the parts of clips 53, and when one sheet is removed another is placed in position by the attendant. The sheets are held against accidental detachment during their travel with the carrier 50 to a point where they receive the coated articles by a belt or apron 55. This belt or carrier 55 at one end passes around a roll or shaft 56 located under the roll 51 and at the other end passes about a roll or shaft 57 located forwardly of the roll 52 and in such a way that the carrier or belt 55 will at its upper surface rest snugly against the lower portion of the apron or belt 50 and will thus retain the sheets of paper against detachment from the clips.

The operator at that end of the machine as soon as one sheet is removed replaces that sheet by another one so that there is a continuous supply of the sheets of paper or other material to meet the requirements of the machine, said sheets being paraffin paper or oiled paper or of any suitable character.

To destroy the plainness of the surface of the coated articles, and to have a more or less fancy decoration thereon means are provided whereby an additional amount of chocolate may be distributed on the articles as they pass through the apparatus and after they pass beyond the air inlet pipe 46. As one means the additional chocolate is formed as a sinuous or wavy line on the articles during the travel of the belt 29. For this purpose a hopper or distributing receptacle 58 is supported to reciprocate on a transversely extending bar or rod 59. The receptacle or hopper 58 has its body 60 of such size as will hold a quantity of chocolate and has an inclined forward wall 61, the upper edge of which at one side is formed to provide a scraper as 62 to remove chocolate from a single collecting wheel or drum 63. The chocolate collecting wheel or drum 63 is substantially the same and operates in the same manner as the wheels 38 and collects the chocolate and moves it in the direction indicated by the arrow and is scraped therefrom and delivered into the body of the hopper 58. The hopper 62 is held to the bar or rod 59 and this rod 59 is guided in the sides of the casing so as to move transversely of the travel of the articles. Each end of the rod 59 may be guided in a bearing 64 and on one side the rod is made cylindrical as at 65 and is connected by a crank 66 to a wheel 67. The wheel 67 is held to a shaft 68 and this shaft 68 is suitably mounted to rotate in brackets 69. The end of the shaft 68 opposite the wheel or disk 67 has a beveled gear 69^a which is in mesh with the gear 70 on a transversely extending main drive shaft 71. The crank or link 66 at one end is held to an adjustable block 72 which is movable in a dove-tailed groove 73 and adjustably held therein so that different throws may be given to the crank 60. This permits the different reciprocatory movements to be given to the rod 59 and hopper or receptacle 58 so that different extents of the wave or curvature of the sinuous line of chocolate distributed on the coated articles may be secured. The bottom of the hopper 58 is provided with a series of openings spaced apart so that each opening is intended to be over or in the line of travel of each coated article and during its travel will form wavy lines on the surface thereof. The hopper is held to the bar 59 by a spring clip 74, Fig. 3, and this clip is adapted to engage either one of two recesses 75 and 75^a. The purpose of these recesses is to permit two adjustments of the hopper 58. In the position shown in Fig. 3 the hopper is in position for use and reciprocates with the bar or rod 59, but by moving the hopper so that the clip will engage the recess 75^a the scraper of the receptacle 58 will be removed out of the path of the collecting wheel 63 so that chocolate will not be fed during the rotary movement thereof to the hopper 58, and this will permit the apparatus to be used without the extra deposit of chocolate as the articles pass through the apparatus.

The casing 24 has openings 76 at the forward and rear portions thereof through which the belt or apron 29 passes and these openings are adapted to be partly closed by means of gates or slides 77, the latter having handles as 78 by which said slides may be forced downwardly so as to place the lower edge thereof in close relation to the upper surface of the belt or apron, leaving sufficient room for the article to be coated to pass into and through the casing, there being a trough or funnel at one side as 79, for filling the receptacle 26 with chocolate.

As a means for rotating and operating the different parts of the machine any suitable mechanism may be employed. As one means the shaft 71 is rotatably held transversely of the machine and on one end of said shaft is the bevel gear 70 for rotating the bevel gear 69 and the shaft 68 which vibrates the hopper 58, while at the other end of the shaft is a suitable clutch 80 having one member, as 81, slidably held on said shaft and its other member 82 loose

on said shaft. A pulley 83 is held to rotate with the clutch member 82 and there is also a sprocket wheel 84 rotatable with the pulley. A sprocket chain 85 passes around the sprocket wheel 84 and around a sprocket wheel 86 on the transversely extending shaft 37 by which the stirrer or mixer 32 is operated. The mixer may thus be rotated constantly while the rest of the machine remains idle in order that the chocolate may be kept in proper condition even when the remainder of the machine is at rest. On the shaft 71 is a spur gear 87 and this gear is in mesh with the gear 88 on the shaft 39 and with the gear 89 on the transversely extending shaft 90 to which the wheel or drum 63 for collecting the chocolate is held and by which the said chocolate wheel is rotated. A sprocket chain 91 extends from a sprocket wheel on the shaft 90 to a larger sprocket wheel on the roll or shaft 31 so as to rotate the latter, and said roll 31 and roll 51 are connected by a short chain 92 to rotate in unison. On the end of the roll 51 opposite the sprocket chain 92 is a beveled gear 93 which meshes with a similar gear 94 on a shaft 95. This shaft 95 may be extensible as by a pin-and-slot connection, as at 96, and at the opposite end thereof is provided with a gear 97 which is in mesh with a gear 98 whereby the rolls and the two aprons 50 and 55 are moved in unison. A sprocket chain 99 passes around sprocket wheels on the shaft 39 and roll 19 by which the conveyer belt 20 is properly moved, thus all of the parts are rotated in unison and from a common drive shaft.

The operation of the invention will be readily understood from the foregoing description when taken in connection with the accompanying drawings. Assuming the parts to be in the position shown in the drawings and the hopper 10 filled with articles to be coated and the pulley 53 rotated after the clutch members are placed in engagement to rotate the shaft 71, the articles in the hopper 10 will be fed to the conveyer belt 20. As the conveyer belt advances the articles are separated by the pins 21 and pass on to the conveyer belt 29. The articles as they pass through the coating apparatus will receive a coating of chocolate from the hopper 41 and be subjected to a blast of air from the pipe 46 to remove the surplus chocolate therefrom. The surplus chocolate passes through the apron 29 back to the receptacle 26. As the apron 29 carries the articles forward a sinuous line or other decoration is placed upon the chocolate by the vibratory movement of the hopper 58 as already explained and from the apron 28 the coated articles pass to the apron 50. The apron 50 contains sheets of paper or other holding means for the articles

and after being conveyed a certain distance may be removed and other paper sheets placed on said apron.

From the foregoing it will be evident that simple and efficient means are provided whereby previously shaped articles may be automatically fed and caused to pass through a coating apparatus, a coating of chocolate placed thereon as the articles are conveyed through the apparatus, and a sinuous line or decorative deposit of chocolate placed upon each article; that simple means is provided whereby the coating material may be evenly distributed on each article and each article coated independently; that simple means is provided whereby the coated articles may be readily removed and handled; and that said machine is simple in construction and entirely automatic in its action.

Having thus described my invention, I claim as new and desire to secure by Letters Patent:—

1. In a machine of the class described, the combination of a reticulated endless traveling apron adapted to support articles to be coated, means for delivering articles upon said apron in rows spaced apart transversely of the apron, a hopper supported above the apron and adapted to deliver a sheet of coating material transversely of the apron to coat the several rows of articles carried thereby, a second hopper supported above the apron and having a plurality of discharge outlets spaced apart transversely of the apron adapted to deliver additional coating material upon the spaced rows of coated articles, means for reciprocating said second hopper transversely of the path of travel of the spaced rows of articles, means interposed between said hoppers for distributing the coating material deposited by the first hopper upon the articles and for forcing the surplus coating material downwardly through the apron, a reservoir for liquid coating material supported beneath the apron and adapted to receive the surplus material forced through the apron, and means for elevating coating material from said reservoir and delivering it into said stationary and reciprocating hoppers.

2. In a machine of the class described, the combination of a reticulated traveling apron, means for delivering a plurality of spaced rows of articles upon said apron, a hopper adapted to deliver a sheet of liquid coating material upon the rows of articles carried by the apron, a second hopper adapted to discharge separate streams of material upon the rows of coated articles traveling with said apron, means for reciprocating said second hopper transversely of the apron, means interposed between said hoppers for discharging a blast of air upon the articles to distribute the coating mate-

- rial deposited by the first hopper and force the surplus material through the reticulated apron, a reservoir supported beneath the apron adapted to receive the surplus material discharged from both of said hoppers and the material removed by the air blast, and independent means for supplying said hoppers with coating material from said reservoir.
- 10 3. In a machine of the class set forth, the combination of a reservoir for plastic decorating material, means for conveying articles to be decorated over said reservoir, a hopper supported above the reservoir and conveying means and having discharge openings spaced apart transversely of the path of the articles, means for reciprocating said hopper transversely of the path of the articles, a dipping wheel rotatably mounted adjacent one end of said reciprocatory hopper to have its periphery pass through the decorating material in said reservoir, and means held to said hopper to reciprocate therewith adapted to scrape decorating material from the dipping wheel and discharge said material into the hopper.
- 15 4. In a machine of the class described, the combination of a reservoir for coating material, a reticulated endless traveling apron for conveying articles to be coated over said reservoir, a coating hopper supported above said apron and reservoir and having a discharge outlet extending transversely across the apron for delivering a sheet of coating material upon the articles traveling with the apron, a decorating hopper supported above the apron and reservoir and having a plurality of discharge outlets spaced apart transversely of the apron, means for reciprocating the decorating hopper transversely of the apron, a dipping wheel rotatably mounted in the reservoir at one end of the coating hopper, means carried by the coating hopper for removing coating material from said wheel and discharging it into the hopper, a dipping wheel rotatably mounted in the reservoir adjacent one end of the reciprocatory decorating hopper, means carried by the decorating hopper for removing material from said wheel and discharging it into said hopper, and means interposed between said hoppers for removing surplus coating material from the articles and forcing said surplus material through the reticulated apron into said reservoir.
- 20 5. This specification signed this 16th day of February A. D. 1916.
- 25 WILLIAM J. WELSH.
